Attorney

UNITED STATES PATENT OFFICE.

THOMAS L. WATKEYS, OF PORT ARTHUR, TEXAS, ASSIGNOR TO GULF REFINING COMPANY, OF PITTSBURGH, PENNSYLVANIA, A CORPORATION OF TEXAS.

COOLING STILL

Application filed November 22, 1921. Serial No. 517,022.

To all whom it may concern:

Be it known that I, THOMAS L. WATKEYS, a citizen of the United States, residing at Port Arthur, in the county of Jefferson and 5 State of Texas, have invented certain new and useful Improvements in Cooling Stills, of which the following is a specification.

This invention relates to cooling stills; and it comprises a method of cooling stills 10 which have been used for the production of gasoline and the like from higher boiling oils with the aid of aluminum chlorid and which contain exhausted aluminum chlorid residues, wherein hot residual oil in the still 15 is displaced by cooler oil and the still is flooded with cold high boiling oil until it is cold or nearly so; all as more fully herein-after set forth and as claimed.

In the manufacture of gasoline and other 20 low boiling oils from higher boiling oils, one of the processes now in use is to heat the high boiling oil with anhydrous aluminum chlorid. In so doing, the high boiling oil, 25 gas oil, for example, enters into ebullition at a temperature below its normal boiling point, giving vapors of lower boiling oils, such as gasoline. By the use of proper 30 methods, large yields of gasoline can be made in this way from various high boiling oils. After a time, the aluminum chlorid loses its activity and becomes converted into a tarry or coky mass. By the use of various 35 expedients, it is possible to remove this residue from the still in greater part, and continue the operation with the addition of 40 fresh aluminum chlorid; but after a time, it is necessary to stop the distillation and cool down the still for cleaning. Sometimes 45 the operation is intermittent and the still is cooled down after the use of a single charge of chlorid. As these operations are ordinarily carried out in large apparatus units, the cooling down offers considerable difficulty. The expedient in use with coking 50 stills and the like of blowing in steam for cooling is not here practical, for the reason that steam instantly produces hydrochloric acid from these residues. And with a 1000 barrel still, bricked up in the usual way and 55 heat insulated, natural cooling after discontinuance of firing may take a week's time.

It is the object of the present invention to provide a simple and economical way of quickly cooling stills of this type. As stated, 60 in the use of aluminum chlorid, distillation

is continued until the aluminum chlorid residues have substantially no further converting activity upon oil. Such being the case, it is practicable in cooling one of these stills to produce a flow of cold oil through it 60 until the whole apparatus is cooled to the desired temperature. In practice I first draw off the aluminum chlorid sludge or coky residue and then displace the hot oil in the still with cool oil, so that the temperature of the hot oil in the still is gradually lowered, and I remove the oil from the still which is being cooled and send it advantageously through cooling coils and thence back to the still or to the stock tank. I may deliver cool oil toward the bottom of the still 65 to be cooled and send the remoyed oil from the still to a cooling coil or to a stock tank direct. The hot oil from the still can not be drawn off and cold oil then admitted, because 70 there would likely be an explosion, due to the sudden generation of the vapors from the cold oil.

In the accompanying drawings I have shown, more or less diagrammatically, apparatus for carrying out my process.

In these drawings, 1 indicates a still, advantageously such as is used in the distillation of higher boiling hydrocarbons with anhydrous aluminum chlorid for the production of lower boiling hydrocarbons. Such stills are usually provided with stirring mechanism, the shaft of which is shown at 2, driven by gear 3, in turn driven by pinion or worm on shaft 4, supported by brackets 5, 80 and driven by pulley wheel 6. The charge of oil, or oil and aluminum chlorid, is admitted at 7 and residual oil and aluminum chlorid sludge or residue may be removed through pipe 8. The still is equipped with 85 vapor line 9 leading to the coolers. The still may be fired by fire box 10. This construction forms no part of my invention.

After operating the aluminum chlorid process for some time, it is necessary to 100 clean out the stills, or it may be necessary to repair them. Before this can be done, the stills must be reduced to a temperature sufficiently low to permit entrance of workmen. Assuming that there has been an 105 aluminum chlorid distillation performed in the still, the heavy aluminum chlorid sludge or coky residue may be withdrawn through pipe 8. There will then remain in the still a considerable portion of hot unconverted 110

higher boiling oil. Higher boiling oil from the oil stock tank 11 may then be sent to the still by means of the pump 12 by means of the valved line 13 entering at a low point in 5 the still and the hot oil in the still is displaced, flowing out near the top of the still through valved line 14, either to the cooler 15 through valved line 16 or back to the stock tank through valved line 17. If the 10 oil is sent to the cooler 15, it may be cooled therein by means of water or the like flowing in at 18 and out at 19, and may then be sent to the pump 12 by means of the valved line 20. Or the oil may be sent from 15 the cooler directly to the stock tank 11 by means of the valved line 21. Or the oil displaced from the still 1 through the line 14 may be sent directly to the stock tank 11 by means of line 17, more cold oil from 20 the bottom of the tank being sent to the still through the line 13.

With the arrangement described it is therefore possible to displace the hot oil in the still by cold oil from the stock tank, or 25 cold oil from the cooling coil, and to gradually lower the temperature in the still. With my process I have been able to lower the temperature in the still within 12 hours to a point permitting entrance of workmen; 30 whereas, when the still is allowed to cool in the usual way, a cooling period of a week or more is necessary. Particularly in the aluminum chlorid stills, it is not possible to cool by means of steam, because the 35 aluminum chlorid used in these stills must be anhydrous and the stills must be kept dry.

I may constantly feed in some fresh cold oil from the stock tank while leading in cold 40 oil from the cooling coils. And if desired I may reverse the flow, supplying cold oil at the top of the still and withdrawing the hot oil from below.

What I claim is:—

45 1. The process of cooling hot stills used in treating oils with a catalytic agent which

is rendered inefficient by contact with water which comprises discontinuing the distillation and displacing the hot residual oil in a still with cooler oil. 50

2. The process of cooling hot stills used in treating oils with a catalytic agent which is rendered inefficient by contact with water which comprises discontinuing the distillation and displacing the hot residual oil in 55 a still with cooler oil, cooling the displaced oil which has become heated and using it for cooling the still and displacing the first used oil.

3. The process of cooling hot stills used 60 in treating oils with a catalytic agent which is rendered inefficient by contact with water containing hot residual oil which comprises discontinuing the distillation, adding cooler oil to the still, withdrawing the mixture 65 and sending it back to the still.

4. The process of cooling hot stills used in treating oils with a catalytic agent which is rendered inefficient by contact with water containing hot residual oil which comprises discontinuing the distillation, adding cooler oil to the still, withdrawing the mixture, cooling it and sending it back to the still. 70

5. The process of cooling stills used in 75 treating oils with a catalytic agent which is rendered inefficient by contact with water containing residual hot oil which comprises discontinuing the distillation, displacing the hot oil in the still by means of cooler oil, 80 cooling the hot oil in cooling apparatus and returning it to the still.

6. The process of cooling stills used in 85 treating oils with a catalytic agent which is rendered inefficient by contact with water which comprises discontinuing the distillation and displacing hot oil therein by constantly circulating cooler oil.

In testimony whereof, I have hereunto affixed my signature.

THOMAS L. WATKEYS.
